UNITED STATES PATENT OFFICE.

JAMES A. TEDDER, OF PRINCETON, WEST VIRGINIA.

WINDOW-SHADE.

1,362,760.

Specification of Letters Patent. Patented Dec. 21, 1920.

Application filed November 6, 1918. Serial No. 261,370.

To all whom it may concern:

Be it known that I, JAMES A. TEDDER, a citizen of the United States, residing at Princeton, in the county of Mercer and State 5 of West Virginia, have invented certain new and useful Improvements in Window-Shades; and I do hereby declare the following to be a full, clear, and exact description of the invention, such as will enable others skilled in the art to which it appertains to 10 make and use the same.

My invention relates to improvements in window shades and more particularly to means for mounting the same.

15 An important object of this invention is to provide a window shade wherein the rolling of the shade upon its roller is controlled by the movement of guiding elements, which guiding elements also serve as a means for 20 retaining the shade in its proper position, when unrolled.

A further object of the invention is to provide a window shade wherein all actuating springs in the roller are eliminated, thus 25 providing a simple and efficient control for the shade.

30 A further object of the invention is to provide novel means of guiding a shade for the purpose of retaining the same relatively straight when lowered and also preventing the lower portion thereof from blowing away from the window when the sash is raised.

35 A further object of the invention is to provide a shade having means for preventing the curtain from being pulled from the roller upon the downward pulling of the curtain.

40 A further object of the invention is to provide means for effectively concealing the working parts of the shade, whereby a highly neat and desirable structure is obtained.

45 A further object of the invention is to provide an apparatus of the character described, which is few in parts, simple to operate, and easy to apply to windows.

50 Other objects and advantages of the invention will be apparent during the course of the following description.

In the accompanying drawings forming a part of this specification, and in which like numerals are employed to designate like parts throughout the same,

Figure 1 is an elevation of a window 55 frame having my improved shade applied thereto,

Fig. 2 is an enlarged fragmentary elevation of my improved shade and associated elements,

Fig. 3 is a horizontal section taken on line 3—3 of Fig. 2,

Fig. 4 is a vertical transverse section taken on line 4—4 of Fig. 2,

Fig. 5 is a front elevation of a bracket 65 embodied in the invention,

Fig. 6 is a side elevation of the bracket showing the same supporting one end of the shade roller,

Fig. 7 is a front elevation of a handle 70 secured to a transverse lift,

Fig. 8 is a fragmentary elevation of one end of the lift, showing the means for engaging the guiding elements, and,

Fig. 9 is a plan view of the structure illustrated in Fig. 8.

In the drawings wherein for the purpose of illustration is shown the preferred embodiment of my invention, the numeral 10 designates a window frame having the usual 80 sash 11 arranged therein.

A solid roller 12 extends transversely of the upper portion of the window frame and has a curtain 13 secured thereto in any desirable manner. Rigidly secured to opposite 85 ends of the solid roller 12 is a pair of pulleys 14. Centrally disposed pins 15 extending from the pulley elements 14 are adapted to be received in brackets 16 carried by the opposed sides of the window frame and 90 adapted to support the shade. As clearly shown in Fig. 2 pulleys 17 are rotatably carried by screws 18 secured to the inner faces of the opposite sides of the window frame. A flexible cable 19 of any desired 95 material is adapted to be arranged upon the pulleys 17 and the pulleys 14. A transverse lift 20 traverses the window and is spaced from the curtain and is provided at its opposite end with guiding elements 21. The 100 guiding elements are provided with horizontally disposed parallel arms 22. A turn-buckle 23 is arranged between the horizontal arms 22 and includes a pair of eyelets 23. As clearly shown in Fig. 2, the eyelets 105 23 receive the cable 19. The turn-buckle 23 is adapted for adjusting the tension of the cable 19 by regulating the eyelets 23 as

is obvious. With reference to the drawings, it will be apparent that an upward or downward movement of the lift 20 will cause the cable 19 to partake of a like movement and thus rotate the roller 12 in the proper direction. A suitable handle 24 is secured to the lift 20 intermediate its ends thereof.

As shown in Fig. 4, the lower portion of the curtain 13 is folded upon itself and 10 stitched for the purpose of forming a transverse opening for the reception of a curtain stick 25. The opposite ends of the curtain stick 25 receive screw eyelets 26 engaging the flexible cable 19. The connections between 15 the lower extremities of the curtain 13 and the cables prevent undue flapping of the curtain.

A window stop strip 27 is arranged on the inner side of the window frame 10. As 20 shown in Fig. 3, the window stop strip 27 is provided with a longitudinally extending groove 28 adapted for the reception of a portion of the working elements of the shade for the purpose of effectively concealing the 25 same. The window stop strip 27 functions as a retaining element or flange, so to speak, and may be said to be L-shaped in cross section. The L-shaped retaining elements 27 extend over all of the working elements 30 of the device with the exception of the inner portion of the cable and the guide elements 21, thereby permitting of the free movement of the curtain and the guide elements.

35 In the use of my invention, it will be apparent that the roller 12 is first arranged in the upper portion of the window frame as shown in Figs. 1 and 2. The cables are now arranged on opposite sides of the roller 40 and pass about the pulleys 14 and 17. The engagement of the eyelets 23 with the cables

retain the cables and the curtain in a set position.

With reference to the foregoing, it will be seen that I have provided a highly simplified shade and actuating mechanism, which is simple to operate and desirable in use.

While I have shown and described the preferred embodiment of my invention, it is understood that I may make such minor changes in arrangement and construction of parts, as will remain within the spirit of the invention and the scope of the appended claim.

Having thus described my invention, what I claim is:—

In combination, a window frame having vertical guide-ways and a roller journaled to the frame and having a curtain wound thereon, pulleys journaled to the lower end of the frame and located in the guide-ways, pulleys secured to the ends of the roller, cables trained over said pulleys, means connecting the free edge of the curtain to the cables, a strip extending transversely of the window, guide elements secured to the ends of the strip and slidably received in the guide-ways, spaced apertured arms formed on said guide elements and located in the 70 guide-ways, eye bolts extending through the arms and having the ends of the cables secured thereto, turn buckles adjustably connecting the eye bolts and located between the arms, and a handle secured to the strip. 75

In testimony whereof I affix my signature in presence of two witnesses.

JAMES A. TEDDER.
